Inventor:
Isidor Heidenreich
By *Reph Taenck*
Attorney.

UNITED STATES PATENT OFFICE.

ISIDOR HEIDENREICH, OF ST. LOUIS, MISSOURI.

ADVERTISING DEVICE.

Application filed August 29, 1921. Serial No. 496,382.

To all whom it may concern:

Be it known that I, ISIDOR HEIDENREICH, a citizen of the United States, residing at the city of St. Louis, State of Missouri, have 5 invented a certain new and useful Improvement in Advertising Devices, of which the following is a specification, reference being had to the accompanying drawing, forming a part thereof.

This invention relates generally to advertising devices and, more particularly, to a certain new and useful improvement in advertising devices of the type commonly known as bill-files or hooks, the principal 15 object of my present invention being to provide an advertising device in the form of a simple, inexpensive bill-file or hook readily convertible or foldable into and out of open or bill receiving condition, the file when 20 closed or folded occupying a small space for convenience in handling and shipping and when unfolded or open being readily suspended upon a wall, desk, or the like and not only providing an efficient file upon 25 which bills, receipts, and other such papers may be conveniently supported, but also affording an attractive advertising medium.

With the above and other objects in view, my present invention resides in the novel 30 features of form, construction, arrangement, and combination of parts hereinafter described and afterwards pointed out in the claim.

In the accompanying drawing,—

Figure 1 is a rear elevational view of an advertising bill-file constructed in accordance with and embodying my invention, the file being shown in full lines as when in folded or collapsed condition; and

Figure 2 is an edge elevational view of the file as when in unfolded or so-called open condition.

Referring now more in detail to the said drawing, which illustrates a practical embodiment of my invention and in which like reference-characters refer to like parts throughout the several views, 1 indicates what may be described as the body-member of the file, which is preferably in the form 45 of a rectangular flat sheet or section of cardboard or other suitable relatively stiff or rigid material, adapted to receive upon its front face the advertising-matter or the like to be displayed.

2 indicates a disk preferably of metal or

other suitable sheet material, which is fixed, as by rivets or the like 3, to and upon the rear face of body 1, as best seen in Figure 1. The disk 2, however, is diametrically bent or displaced upon itself, as at 4, so 60 that approximately the upper half of the disk is offset to extend flatwise relatively to, but in somewhat spaced relation from, the rear face of body 1, as best seen in Figure 2.

Provided in the upper portion of disk 2, 65 is an aperture or opening 5, for purposes shortly appearing; and provided in the bend 4 is a perforation or aperture, as at 6, in alignment with which latter aperture to provide a so-called slide-way trending longitudinally of body-member 1, is a third aperture formed, as at 7, through the upper end of an offset or displaced portion 8 provided in the disk 2 at and adjacent its lower marginal edge, as shown. 75

Disposed for both slidable and rotary movement in the slide-way so provided, is the elongated stem 9 of the file-member proper, which member is composed of a single section of suitable wire bent within 80 its length to integrally include a pronged bill-engaging portion 10 at one or the lower end of the stem 9 and a hook 11 at the other or upper end of the stem 9, as seen in both Figures 1 and 2, the hook 11 being adapted 85 for interlocking engagement with disk-aperture 5 for purposes also shortly appearing.

In use or operation, when it is desired to close the file, as, for instance, in packing or shipping, the stem 9 of the file-member is 90 slidably moved lengthwise in its slide-way towards the upper or top edge of the body-member 1, its movement in such direction being limited by engagement between its pronged end-portion 10 and the lower edge 95 portion 8 of the disk 2. The file-member as a whole is then rotarily moved relatively to the body-member 1 to lie compactly approximately flatwise upon the rear face of body-member 1, as seen in full lines in Figure 1, and I may add that the file-member, including its stem 9 and pronged end portion 10, is preferably of such dimensions relatively to the body-member 1 that when in such folded or inoperative position, the 100 file-member is confined entirely within the area of the body-member 1, as also seen in Figure 1.

When it is desired to open and use the file, the file-member is slidably moved down- 110

wardly in its slide-way towards the lower edge of the body-member 1, as indicated by dotted lines in Figure 1, and then reversely 5 rotary moved to project its pronged end-portion 10 forwardly below the lower edge of, and approximately at right angles to, the body-member 1, as illustrated in Figure 2, conveniently accessible for the placement thereupon of bills, papers, letters, and the like. The hook 11 of the file-member is now 10 removably sprung into its co-operating disk-aperture 5 and the pronged end-portion 10 of the file-member, as well as the file-member as a whole, thereby releasably locked in 15 such open, operative position. By means now of a preferably re-inforced opening or aperture 12 provided for the purpose in the body-member 1 adjacent its upper edge, the device as a whole may be conveniently suspended 20 upon a wall, desk, or the like, efficiently then serving the function not only of a bill-file, but also of a displaying medium for advertising matter or the like appearing upon the front surface of body-member 1.

My new file is very simple in form and construction, may be inexpensively and economically manufactured, may be readily folded to occupy a small space, as in packing and shipping, may be conveniently opened and locked in operative paper-filing and advertising display condition, and when open or unfolded provides both a convenient bill-file and an attractive advertising medium.

I am aware that changes in the form, construction, arrangement, and combination of the several parts of my new advertising device may be made and substituted for those

herein shown and described without departing from the nature and principle of my invention. 40

Having thus described my invention, what I claim and desire to secure by Letters Patent is: 45

A device of the kind described including a body-member in the form of a flat section of material providing an advertising display surface, a second member fixed upon the rear face of the body-member with a portion of its area offset and spaced from the body-member, the offset portion having a single aperture and the second member having a plurality of additional aligning apertures forming a slide-way, and a file member proper integrally comprising a pronged end-portion and an elongated stem having a hook upon its opposite end, the file member being disposed at its stem for 50 slidable and rotary movement in said slide-way into and out of operative position relatively to the body-member, the file member when in inoperative position lying to the rear of, and approximately flatwise relatively to, the body-member and when in operative position extending with its pronged end-portion disposed forwardly and below the lower edge of, and approximately at right angles to, the body-member, the file member being adapted to removably fit at 55 its hook in said single aperture of the second member when in operative position for releasably locking the file member in such position. 60

In testimony whereof, I have signed my name to this specification. 65

ISIDOR HEIDENREICH.
